SHOE CLEANER

Robert E. Ellis, 700 E. School St., Centerville, Ind.
Filed June 8, 1960, Ser. No. 34,739
7 Claims. (Cl. 15—37)

This invention relates to a mechanical device automatically operating upon a person standing upon a plurality of brushes for cleaning the undersides of the soles of shoes.

The device would normally be positioned adjacent and opening into an office or a room, or at any place where it is desired that the shoes be cleaned before mud which might have been on them would be tracked into a room or other space.

A primary purpose of the invention resides in the fact that shoes will be cleaned by a person stepping on the brush area, whereupon the brushes will start moving to brush off the shoes from their undersides, and the device will quit operating when the weight of the person is removed from that area.

A further important object of the invention is to provide such a device in an extremely simple and yet durable operating mechanism. A still further important object of the invention resides in providing means for preventing freezing of the device in below freezing weather.

A still further important object of the invention resides in the fact that even the shoes of women having spike heels may be cleaned without the heels becoming engaged in or entangled in the brushing mechanism.

These and many other objects and advantages of the invention will become apparent in the one particular form of the invention as illustrated in the accompanying drawings, in which:

FIG. 1 is a view in top plan of a structure embodying the invention;

FIG. 2 is a view in top plan and partial section of the device with the top cover removed;

FIG. 3 is a view in transverse section on the line 3—3 in FIG. 2;

FIG. 4 is a view in vertical transverse section from the end of the device and on the line 4—4 in FIG. 2;

FIG. 5 is a view in vertical section in detail of a brush supporting bar spring mounting;

FIG. 6 is a view in bottom plan of the device;

FIG. 7 is a detail in top plan view of a short length of a brush member;

FIG. 8 is a view in vertical section on the line 8—8 in FIG. 7;

FIG. 9 is a view of the wiring diagram in pictorial representation and

FIG. 10 is a detail in transverse vertical section through a motor switch operating device.

A generally rectangular box 10 is provided at one end 11 with a pair of spaced apart brackets 12 and 13 fixed to the opposite side walls of the box. Each of these brackets is generally C-shaped, and receives the end of a support bar 14. The support bar 14 has an end portion 15, one at each end, entering the brackets 12 and 13, and there is a pin 16 down through each bracket slidably passing through the ends 15, and through a compression spring 17, FIG. 5, and on into the lower portion of the bracket in each instance. The support bar 14 thus is urged upwardly to within the limits of the opening in the brackets by means of the spring 17. The pin 16 in each instance retains the bar 14 in alignment approximately parallel with the end 11 of the box 10.

A second pair of like brackets 19 and 20 are fixed to the side walls of the box 10 at a distance from the first pair 12, 13, herein shown as being spaced beyond the transverse center of the box 10. A support bar 21 is supported by the brackets 19 and 20 in the same manner as is the support bar 14 in its brackets.

2

A plurality of parallel aligned shafts 22 extend between and rockably through the two supporting bars 14 and 21. Each of these shafts 22 extends through a brush holder body 23, FIG. 8, substantially throughout the entire length of each shaft between the two bars 14 and 21. These bodies 23 are fixed to the shafts 22 in each instance so that the bodies 23 will rock when the shafts 22 rock or rotate.

Each body 23 carries a rectangular groove across its upper side, FIG. 8, and a brush holder 24 is frictionally carried within the groove which is by the numeral 25. These brush carriers 24 may thus be replaced from time to time as the brushes may wear. Preferably, each brush holder extends not more than one-half the length of the body 23, so that, FIG. 2, the brush holders may be staggered, every other body 23 having a brush holder with bristles 26 extending to approximately the center of the distance between the two supporting bars 14 and 21.

A post 27 is fixed to the underside of each body 23 and extends downwardly to be fixed in a trunnion block 28, FIG. 3. A pin 29 is fixed in each trunnion block 28 to extend from one side thereof, rockably through a reciprocating bar 30. This bar is of that length which will extend throughout the length of the supporting bars 14 and 21, FIG. 3. The bar 30 is maintained in its rocking connections with the various pins 29 by any suitable means, herein shown as by cotter pins 31. A compression spring 32 is preferably provided to surround the endmost post 27 to yieldingly abut by its opposing ends the undersides of the supporting bars 14 and 21 in the topside of the reciprocating bar 30. This normally maintains the bar 30 in that position where the posts 27 will be vertically disposed, and in any event will take up lost motion between the two bars so as to reduce noise and give a smoother working action.

There is a transverse plate 33 extending across the box 10 spaced from the supporting bar 21 and the reciprocating bar 30. A motor 34 is mounted within the box 10, FIG. 2, and through any suitable transmission means, herein shown as a belt 35, a shaft 36 is rotated. This shaft 36 is extended through the plate 33 and fixedly engages the free end of a crank arm 37, FIG. 3.

A connecting rod 38 has one end rockably engaged to the opposite end of the crank arm 37, FIG. 3, and its other end in a rocker head 39 rockably supported on the reciprocating bar 30. Thus when the motor 34 operates, the reciprocating bar 30 will be reciprocated transversely of the box 10, and consequently the brushes 26 will rock to and fro in unison. The rocking of these brushes of course is centered at the axes of the shafts 22. These brushes being spaced apart, offer openings therebetween. These openings are enclosed by shields 40 and 41 fixed to the sides of the upper portion of the bodies 23, FIG. 8. These shields 40 and 41 have upper convex surfaces substantially at their highest points at the lower ends of the exposed bristles 26. For cleaning purposes, each of the shields 40 and 41 is preferably provided with a series of holes 42 therethrough.

There is a floor spaced below the brushes within the box 10. This floor is designated by the numeral 43 and this floor 43 slopes from an upper position as indicated in FIG. 4 to drain over an edge 45 into a trough 46 which slopes from one side of the box to the other side and has drain holes 47 therethrough at the lowermost zone, these holes 47 opening up into a drain tube 48. Any dirt and water being removed from shoes falls onto the floor 43, and when sufficient moisture is present, will be washed down into the trough 46 and out through the waste or drain tube 48 to be conducted to any suitable place. Normally the device will be flushed out by any suitable means such as by a hose in order to remove the accumulated dirt.

A switch box 49 is mounted on the floor 43 about midway of the lengths of the bodies 23, FIG. 2. A push button 50, FIG. 9, extends upwardly from the box 49 to operate the switch therein. This switch is not shown herein in detail other than in the diagrammatic form in FIG. 9 since it is of the usual and conventional quick acting type. There is an arcuate push plate fixed to the under side of that body 23a which passes across the box 49. The button 50 is centered centrally of the body 23a, and there is shoe 51 fixed to the under side of the body 23a to be over the button 50 and normally spaced therefrom by means of the springs under the ends of the support bars 14 and 21. When the individual steps onto the brushes, the resistance of the springs holding the supporting bars 14 and 21 upwardly is overcome so that the various bodies 23 are lowered, and in so doing, the body 23a, brings the shoe 51 down against the button 50 and closes the switch therein. Closure of this switch closes a circuit from a power line 52 through the motor 34 and starts the bodies 23 to rock back and forth so that the bristles 26 will brush the under sides of the shoes in a reciprocating manner. When the individual steps off of the device, the springs under the ends of the supporting bars 14 and 21 will return the brushes to their uppermost positions, and lift the shoe 51 from the switch button 50 and thus open the switch to stop the motor 34.

Since the device will work in the wintertime to clean snow off of shoes as well as mud and dust in the summertime or in above freezing weather, snow dropping off of the shoes down between the bristles 26 and the bodies 23 would normally accumulate on the floor 43 and freeze theron. In order to overcome that freezing action, the under side of the floor 43 carries a heating element 54, having a thermostatic element 55 in the circuit, FIG. 6, the thermostat element 55 normally being open in weather above a temperature of 32 degrees and closing the circuit when the temperature drops therebelow. Thus the floor 43 is automatically warmed by the heating coil 54. The coil 54 is also wrapped around the drain tube 48 to prevent freezing therein.

There is a grating 60 fixed over the box 10. This grating 60 has slots 61 therethrough defined by the intervening bars 62, are coextensive with the lengths of the brushes 26, and sufficiently wide to permit the rocking of the brushes 26 without hindrance from the margins of the slots. The guards 40 and 41 are under those bars 62, and rock in close proximity to the bars.

Therefore it is to be seen that I have provided a very simple but most effective combination for cleaning the soles and edges thereof of shoes, with a minimum number of elements, providing a durable and comparatively low cost device. While I have herein shown the device in the one particular form, I do not desire to be limited to that precise form beyond the limitations which may be imposed by the following claims, in view of the fact that mechanical variations in parts may be employed without departing from the spirit of the invention.

I claim:

1. A shoe cleaner comprising a plurality of elongated bristle brushes; elongated bodies holding the brushes in laterally spaced apart rows; a pair of body support bars rockably carrying said bodies therebetween; means carrying said bars confining the bars to vertical travel; said carrying means including means yieldingly maintaining the bars at uppermost positions; a fixed grating having longitudinal slots through which the bristles of said brushes extend; a post depending from each of said bodies; a rock bar; means rockably engaging said posts with said rock bar; a drive shaft; means eccentrically engaging said rock bar with said drive shaft; whereby the rotation of

said drive shaft causes said rock bar to reciprocate such that said brush bodies are rocked to and fro; a motor for driving said shaft; an electric switch having an actuating member; a shoe member fixed to the underside of one of said elongated bodies and being located in the path of said actuating member whereby the downward travel of said brushes causes said actuating member to close said switch and to energize said motor; said motor and said electric switch being electrically interconnected in a power circuit.

5 2. The structure of claim 1 in which there is a shoe heel shield carried on sides of said bodies below upper ends of said bristles and under said grating, effectually closing the spaces between said brushes, and, with said 10 brushes, said slots.

15 3. The structure of claim 1 in which there is a shaft extending from the ends of each of said elongated bodies rotatively engaged by said body supporting bars; and said 20 carrying means comprising a bracket receiving ends of the supporting bars therein; said vertical travel confining means comprising a guide vertically directed and retaining the bar ends in said vertical travel; and said yielding means comprising springs carried by the brackets, said 25 bar ends resting on the springs.

25 4. The structure of claim 1 in which said posts extend downwardly one each from said elongated bodies and at common ends thereof; said bodies being grooved longitudinally along their upper sides; and said brushes have bristle holders frictionally retained in said grooves against longitudinal travel therealong.

30 5. A shoe cleaning device operated by shoe pressure thereagainst comprising a support generally box-shaped and having a floor therein sloping toward drain means; a grating having spaced apart bars covering the support 35 and above said floor; a pair of brackets, one at each side of the box adjacent one end thereof; a second pair of brackets spaced along the box from said end; a support bar shiftably carried by each said pair of brackets and confined to vertical travel; spring means carried by the 40 brackets supporting the bars at an uppermost degree of said travel; a plurality of side-by-side spaced apart bodies; a brush unit carried by each of said bodies with bristles extending upwardly therefrom between said grating bars; rocker pins extending from ends of the bodies; said support bars having bearings receiving said pins thereby 45 supporting and maintaining the spacing apart of the bodies; a connecting bar pivotally interconnecting said bodies at common distances from the axes of said pins; electrical drive means longitudinally reciprocating said connecting bar; switch means controlling said electrical 50 drive means; said switch means being actuated by down-travel of said bodies.

55 6. The structure of claim 5 in which there is a shoe member on one of said bodies having an arcuate under surface maintaining substantially a constant pressure on said switch means during depression of said one body.

60 7. The structure of claim 5 in which there is a shoe heel shield fixed to sides of said bodies extending laterally therefrom under said grating bars, forming in combination with said brushes a closure between the grating bars at all degrees of rocking of the bodies.
